(57) CLAIM

We claim the ornamental design for a cap, as shown and described.

DESCRIPTION

FIG. 1 is a top plan view of a cap showing our new design; FIG. 2 is a side plan view thereof; and, FIG. 3 is a bottom plan view thereof.

The dotted lines are intended to show features that are environmental only and form no part of the claimed design.

1 Claim, 3 Drawing Sheets

FIG. 1

FIG. 3
